JOHN J. HOEY, OF PROVIDENCE, RHODE ISLAND.

CLOTH-CLAMP FOR TENTERING-MACHINES.

1,191,512.

Specification of Letters Patent.

Patented July 18, 1916.

Application filed December 2, 1915. Serial No. 64,763.

To all whom it may concern:

Be it known that I, JOHN J. HOEY, a citizen of the United States, residing at Providence, in the county of Providence, State of Rhode Island, have invented certain new and useful Improvements in Cloth-Clamps for Tentering-Machines, of which the following is a specification.

My invention relates to tenter-clips or cloth-clamps for use on tentering-machines employed in finishing textile fabrics and consists of improvements in the means for hingedly mounting the movable jaw on the clip.

15 The object of my improvement is to provide for hinging the swinging jaw in such manner that it may be more conveniently and easily removed for repair or replacement without requiring the disconnection of the clip from the chain of which it forms a part, or without necessitating moving the chain to bring the clip into position on the end sprocket-wheel so that it can be displaced from alinement with the other clips

20 in the series.

The manner and means for carrying out my improvement are fully described in the following specification, illustrated by the accompanying drawings, in which like reference characters designate like parts.

In the drawings:—Figure 1 is a side elevation of my improved tenter-clip showing the arrangement for hinging the movable jaw on the frame of the clip; Fig. 2, a front elevation of the same illustrating the manner in which the clips are linked together in an endless chain; Figs. 3 and 4, detail views showing a modification in the form of the jaw-hinging means; and Figs. 5 and 6, detail views showing a still further modification of the invention.

Referring to the drawings, the main elements of the clip here illustrated are of well known construction as generally employed in this art, but it is to be understood that my improvement is adaptable to other forms of clips with only slight modifications in its structure. The clip here shown comprises the main frame C formed with a base portion having a lower shelf-like jaw-member J and two upstanding arms c, c' overhanging the top of the jaw. At either side of the frame C are suitable lugs or tongues t, t' adapted to be fitted in male-and-female fashion to correspondingly formed tongues on adjacent clips to link them together in an

endless chain as shown in Fig. 2. The clips are coupled together by means of suitable hinge-pins p, p, etc., and their under portions are provided with openings o adapted to receive the teeth of the sprocket-wheels around which the chain of clips travels. Usually two sprockets are provided for each chain, arranged at opposite ends of the frame on which the chain travels in the well known manner usually employed in tentering-machines.

Pivoted at the ends of the overhanging arms c, c' is the movable jaw B arranged in pendant relation to the main frame of the clip with its lower, sharpened edge b adapted to bear on the top of the fixed jaw J. The fabric is inserted between the jaws J and B and as it is pulled out away from the clip its selvage is gripped and held by the dogging action of the movable jaw B in the usual manner. The movable jaw B is formed with upstanding ears or lugs b', b'' adapted to straddle the ends of the arms c, c', to be hinged thereto by means of a pivot-pin or rod R inserted therethrough. Heretofore in all arrangements of clips generally employed in the art the pivot-pin is merely inserted through suitable holes in the arms c, c' and lugs b', b'' and held in place by a cotter-pin or other similar fastening-means. Such an arrangement, however, necessitates the complete longitudinal withdrawal of the pivot-pin before the jaw B can be removed and therefore requires that the clip be displaced from alinement with the other clips in the chain. It will be noted from Fig. 2 that the clips are linked together in close relation so that when the chain is stretched out along the frame of the machine there is not sufficient room between the clips to draw out one of the pivot-pins which hold the movable jaws in place. It is frequently necessary to remove the jaws for grinding their operating edges, or to replace them when they become too badly worn or broken. With the usual arrangement of pivoting-means, as above described, when it becomes necessary to take out one of the jaws either the whole clip must be detached from the chain or else the chain must be traveled along the frame until the clip to be operated upon is brought into position on the end-sprocket. That is to say, the usual practice is to travel the chain along the frame until the clip to be repaired rides onto the end-sprocket, and this will

cause it to be rocked to displace it from alignment with its adjacent clips. This allows the pivot-pin to be slid its whole length out from the bearings, but often the 5 clip which requires repairing is at a considerable distance from the end-sprocket when the chain stops and this necessitates starting the machine up again or turning the sprockets by hand. This is often very inconvenient 10 especially if the cloth is in the machine, and in any event the operation requires considerable time and effort which it is desirable to avoid. To obviate this necessity of displacing the clips from alignment to allow 15 the removal of the pivot-pin I have devised an ingenious method of mounting the pin in its bearings to provide for its lateral withdrawal as next described:

Referring to Fig. 2, the right-hand arm c' 20 of the clip C is here shown as being slotted at s on its front to allow the lateral displacement of one end of the pivot-pin or rod R after its opposite end has been withdrawn from the other bearing c . As illustrated in Figs. 1 and 2 the bearing hole c^2 in the arm c' is bored somewhat larger than the diameter of the rod R and a bushing D is inserted in the bore to receive the rod. To hold the rod R in place in its bearings 25 30 the arm c' , bushing D and rod R are provided with alining holes h through which a cotter-pin E is inserted, see left end of Fig. 2.

Fig. 2 illustrates three adjacent clips 35 linked together in alignment with the central clip C shown with its jaw B ready for detaching. The removal of the jaw B is accomplished as follows: The cotter-pin E is first drawn out from the hole h and the 40 bushing D is then slid to the left beyond the side of the bearing c' . The rod R is next drawn out to the right, as shown in connection with the central clip C in Fig. 2, to bring its left-hand end clear of the 45 bearing c . The pin or rod R can now be drawn out laterally through the slot s in the arm c' and the jaw B is thus removed clear of the frame of the clip C. To replace the jaw B it is only necessary to slide the 50 rod R through the lug b^2 of the jaw B and through the bushing D, and to then slip the rod through the slot s in the bearing c' . The several bearings b^2 , c , c' and D are then brought into alignment while 55 the rod R is pushed through the bearing c and lug b' and the bushing D slid into the enlarged hole c^2 in the bearing c' . By turning the rod and bushing their transverse holes may be brought into alignment with the hole in the bearing c' to allow the insertion of the cotter-pin E to secure the several 60 parts in place.

In Figs. 3 and 4 I have illustrated a somewhat simpler and preferred form of 65 the invention as now described: In this

modification the bushing D is dispensed with and the bearings c and c' are both bored to the same diameter to adapt the pin R to fit freely therein. The bearing c' is slotted on its front, as in the first described arrangement, but in this instance the slot s' is somewhat less in width than the diameter of the rod R. This provides that normally the rod R will be held against lateral displacement from the bearing c' , 70 but to allow for its sidewise removal the rod is flattened off on opposite sides at r , r at a point substantially equidistant from its ends. The rod R is normally held from sliding or turning in the bearings c , c' by 75 means of the cotter-pin E, as before described, and to remove the rod it is only necessary to withdraw the pin to allow the rod to be slid to the right. As soon as 80 its left-hand end is drawn clear of the bearing c its flattened portions r , r will have been brought into alignment with the bearing c' and the rod can then be drawn out through the slot s' . Instead of having its side flattened off at r , r the rod R might be turned down 85 to a less diameter at this point to allow for its withdrawal through the slot s' .

In Figs. 5 and 6 I have illustrated still another embodiment of the invention in which the parts are constructed as follows: 90 As shown in Fig. 5 both bearings c , c' are slotted on their sides at s^2 , s^2 and the rod R is formed with two flattened portions r' , r' and r^2 , r^2 at its ends. With this arrangement the rod may be slipped into and out 95 from the bearings c , c' without any endwise movement thereof. With the rod R in place in its bearings as shown in Fig. 5 it is turned to bring its rounded portions in position at the top and bottom of the bores 100 in the arms c , c' and its transverse hole h' will then aline with the vertical hole h in the arm c' , see Fig. 5. The cotter-pin E is then pushed down through the holes h , h' to prevent the rod from turning and to 105 also secure it from longitudinal displacement. By withdrawing the cotter-pin the rod may be turned to allow for its lateral movement 110 out through the slots s^2 , s^2 . While this arrangement provides, possibly, the most convenient method for removing the rod R and the jaw B, in some respects it is not as practical as the construction shown in Figs. 115 3 and 4 because the rod is weakened somewhat by the flattening of its sides and furthermore does not have as full a bearing in the arms c , c' . However, it will be seen that this construction accomplishes the purpose desired and therefore it may be substituted for either of the other forms of 120 125 the invention as shown.

It will be observed that with any one of the above described arrangements the movable jaw B may be removed from the clip C without withdrawing the pin or rod R 130

clear through the bearings c, c' . That is to say, the rod may be freed from its bearings in the clip by a lateral displacement without interference with the adjacent clip 5 in the chain. As shown in Fig. 2 the arrangement of the clips when linked together in the chain is such as to provide sufficient clearance for a slight movement of the rod R , so that it is not necessary to displace one 10 clip from alignment with the other. My improvement therefore provides for easy and convenient removal and replacement of the jaws of the clips without disconnecting the latter from the chain or without requiring the slow, laborious work of traveling the chain to bring the clip to be operated upon into position on the end-sprocket.

Various modifications other than those here shown might be made in the construction and arrangement of the parts of my improved device without departing from the spirit or scope of the invention.

Therefore, without limiting myself to the exact embodiment shown, what I claim is:—
25 1. In a cloth-clamp for tentering-machine chains, the combination with the frame of the clamp provided with bearings, of a hinge-pin mounted in said bearings, means to allow the hinge-pin to be withdrawn laterally from the bearings, and a movable jaw pivoted on the hinge-pin to adapt it to be removed therewith for repair or replacement.

2. In a cloth-clamp for tenter-chains, the combination with the frame of the clamp provided with bearings having alining bores, of a hinge-pin mounted in said bearings to allow for its lateral withdrawal from the frame, a movable jaw-member pivoted to swing on the pin, and means to secure the hinge-pin against displacement from its bearings.

3. In a cloth-clamp for tenter-chains, the

combination with the frame of the clamp provided with a fixed jaw, of a hinge-pin 45 mounted in a slotted bearing on the frame to allow it to be withdrawn laterally therefrom, means to secure the pin against displacement from the bearing, and a movable jaw pivoted on the pin to adapt it to co-operate with the fixed jaw to clamp the cloth thereagainst.

4. In a cloth-clamp for tenter-chains, the combination with the frame thereof provided with arms having bearings at their 55 ends, and one of said bearings slotted through its side, of a hinge-pin mounted in said bearings and formed with a portion of reduced thickness to adapt it to be withdrawn through the slot in the bearing, 60 means to secure the pin against displacement from its bearings, and a movable jaw pivoted on the hinge-pin to adapt it to swing on the frame.

5. In a cloth-clamp for tentering-ma- 65 chines, the combination with a fixed-jaw member and a movable-jaw co-operating therewith, of bearings on the fixed-jaw member provided with alining bores and one of said bearings having a transverse slot cut 70 through its side, of a hinge-pin extending through the bearings to support the movable jaw in pivotal relation to the fixed jaw, means for securing the hinge-pin against displacement from the bearings, and means 75 whereby the hinge-pin may be withdrawn laterally from the slotted bearings after its end has been slid free from the other bearing.

In testimony whereof I affix my signature 80 in presence of two witnesses.

JOHN J. HOEY.
